In Germany May 16, 1936

5 Claims. (Cl. 178—44)

The present invention relates to a coupling transformer for use in amplifier circuits for amplifying very wide frequency-bands particularly for intermediate frequency amplifiers for television reception or transmission, which transformer complies with the requirements existing in such circuits operating with a good amplification for a very large width of frequency band. The subject matter of the present invention relates not to a transformer with purely inductive coupling, but to a transformer with a combined inductive-capacitative coupling effect, which is adjusted by special arrangement of the windings and the circuit. Further, the transformer according to the invention makes use of the phenomenon of the two coupling waves in the case of a very tight coupling, and employs accordingly a tight coupling of such nature that the spacing of the two coupling waves corresponds to the width of frequency band to be transmitted. In accordance with the invention in a high-frequency circuit for the uniform amplification of very wide frequency bands more particularly for television purposes the coupling arrangement represents a transformer having windings connected with each other in a definite manner consisting of coils arranged coaxially in single-layer fashion on the same axis the primary of which is divided into two winding-coils arranged on either side of the secondary and wound in the same direction.

The invention will be clearly understood by way of example shown in the accompanying drawing in which:

Fig. 1 shows a transformer arrangement according to the invention connected between two amplifier tubes.

Fig. 2 is a simplified form of Fig. 1 and shows the additional capacitative coupling effect between primary and secondary and

Fig. 3 shows several frequency curves from which the effect of the coupling arrangement according to the invention may be recognised.

In Fig. 1 the coupling transformer 1 is shown in conjunction with two tubes 2 and 3. The coupling transformer consists of a primary winding, which is divided into two winding coils 4 and 5, and a secondary winding coil 6. All three windings 4, 5 and 6 are wound in the same direction. According to the invention, the high-potential ends of the primary half 5 and of the secondary 6 are situated immediately adjacent to the secondary coil 6. Accordingly that end of the primary winding 5 beginning at 7 is arranged close to that end of the secondary beginning at 8. The secondary and primary coils are earthed at

9 and 10 respectively via a condenser. In addition the primary coil and the secondary coil are each damped by a resistance 11 and 12 respectively.

By reason of the special circuit arrangement of the transformer coils in accordance with the invention and its primary coils situated on either side of the secondary coil in single-layer fashion as set forth in Fig. 1 there is obtained a very considerable broadening of the frequency response band and an improvement of the transmission in the range of the higher side band frequencies, necessary for obtaining a large width of band.

The connection between the windings are shown in a simplified form in Fig. 2. The point 7 designates the high-potential end of the primary; the primary winding coils 4 and 5 are connected in series, and the point 10 designates that end of the primary which is earthed. The primary current, flowing from the anode of valve 2, passes in the case of high frequencies not only to the primary winding 5, but at the same time also for a large part by way of the stray capacity 13 to the secondary coil 6. In Fig. 2 the line current is designated by 14 and the reactance current produced by the capacity 13 is designated by 15. By reason of this proportion of reactance current 15 there results in the secondary winding, which is earthed at 9, an additional drop in potential which with the stated polarity assists the induced potential. The signs of both potentials are the same and opposite to the sign of the potential at the primary terminal 7.

The effect of this capacitative auxiliary coupling via capacity 13 is shown in the curves *a* and *b* in Fig. 3, wherein the ordinate represents the transmission degree and on the abscissa there are plotted the single frequencies to be transmitted. The curve *b* is the transmission curve obtained over the whole frequency band for the polarity of the connections according to Fig. 2 and curve *a* is the transmission curve obtained when the connections to the secondary winding 6 are reversed. The resistances 11 and 12 are omitted in both cases *a* and *b*. The curve *c* is produced by using damping resistances.

The band width covered by the transformer is determined by the degree of inductive coupling between the primary windings 4, 5 and the secondary 6. The required degree of coupling may be attained with the transformer according to the invention having three co-axially disposed coils by suitable adjustment of the axial lengths of the coils by suitably selecting the diameter of

the wire employed. The magnitude of the capacitive coupling is determined mainly by the distance a between coils 5 and 6. In accordance with the invention, it may, if desired, also be 5 adjusted by displacing over said coils an insulated ring 16 of conductive material, which is slotted in one place along a plane passing through its axis for avoiding eddy currents.

The tuning of the two windings is effected by 10 so dimensioning the coils that with their self-capacities and the valve capacities and stray capacities they resonate at the desired frequency. All unnecessary parallel capacities are avoided by making the capacities of the structure and 15 the supply conductors as small as possible. The smaller these are, the greater may be chosen the self-inductance by corresponding increase of winding-turns, and accordingly the greater is the 20 amplification which can be attained. The tuning of the coils takes place initially in single fashion on the same wave in respect of the primary and secondary coils. The splitting up into coupling waves occurs by very tight coupling. The degree 25 of amplification is determined roughly by the slope S of the valve characteristics by the amount of the detrimental anode capacity of the valves, by the carrier frequency f and by the frequency band width B to be transmitted, which in the carrier frequency method appears as double 30 width of band in the spacing of the side frequencies.

When operating with constant primary potential both peaks of the frequency curve a according to Fig. 3, in the case of proper connection, and of the frequency curve b in the case of reverse polarity of the secondary have the same height. When employing screening grid tubes, however, which alone preferably are used, the transformer is excited not at constant potential 35 (case of idle running), but at constant radio-frequency current (case of short-circuit). In this case the radio frequency across the terminals of the primary winding 4, 5 is not constant but varies with the frequency dependent upon the 40 impedance of the primary winding 4, 5, which impedance again has the character of a resonance curve. In this way the radio frequency potential produced across the secondary winding is increased in the neighbourhood of the resonance 45 frequency of the primary winding with the result that the resultant overall response curve has two peaks of unequal height. This effect is very disturbing when a plurality of these units are connected in cascade, because the resonance 50 peaks of the successive stages become multiplied together. In practice, therefore, any method which enables an approximation to the ideal frequency curve of the single transformer to be obtained is very important. For this purpose in the 55 circuit arrangement according to the present invention the following measures are most advantageous and most important.

1. Adjustment of the damping resistance 11 lying in parallel to the primary side, in such 60 manner as to have a value being smaller than the primary impedance of the transformer in the frequency band employed. In this way there is certainly a loss of amplification, but one obtains an approximation to the state of idle running 65 and the transformer is excited at substantially constant primary potential.

2. Disposal of the natural wavelength of the secondary coil in the wave range, i. e., in the 70 range of the higher side-band frequencies, in order to permit there of an increase of the re-

sulting frequency curve. This method requires to be adopted only to small extent to be successful, as a small displacement of the resonant range of the secondary coil into the short-wave range has the double effect of improvement in this range and a deterioration in the long-wave range, i. e., in the range of the lower side-band frequencies. The secondary coil is damped only to such extent by a resistance 12 that the same has no further oscillatory properties (aperiodic 10 damping: $\omega L = R$). The damping by the resistance 12 may be much smaller than the damping by resistance 11. The frequency curve c according to Fig. 3 is practically attained for a coupling transformer according to Fig. 1 by using 15 following data:

Number of image lines: 400.

Width of frequency band 2.25 megacycles.

Carrier frequency 7.5 megacycles.

Primary damping resistance 11:2,000 ohms. 20

Primary inherent parallel capacity approx. 15 cm.

Secondary damping resistance 12:5,000 ohms.

Natural wave lengths: primary=7.5 megacycles. 25

Secondary=8 megacycles.

Length of winding for all three coils approximately 2-3 mm.

Spacing $a=b=1$ mm.

The curves a and b set forth in Fig. 3 are attained without using damping resistances, and clearly show that the long-wave maximum is higher than the short-wave maximum. The curve c in Fig. 3 shows the result of the correcting measures according to the invention. The capacitive coupling may be governed by the spacing a and the inductive coupling by the spacing b . In this way the two peaks of the frequency curve may be made of equal height.

I claim:

1. A high frequency transformer for coupling amplifier circuits used for uniform amplifying of very wide frequency bands, more particularly for television purposes comprising a primary and a secondary winding connected between the circuits to be coupled and coupled so tightly as to have a wide frequency resonance curve corresponding to the desired width of frequency band produced by reason of the arising two coupling waves, said primary and secondary coils the resonant frequencies of which are determined by the inherent capacities being arranged in single-layer fashion co-axially on the same axis, said primary being divided into two winding coils arranged on either side of the secondary and wound in the same direction, the high potential ends of one of said primary coils and of the secondary being arranged closely to one another so that the additional capacity coupling between said one primary coil and the secondary is more effective between said one primary coil and said secondary than between the other primary coil and said secondary.

2. A high frequency transformer for coupling amplifier circuits used for uniform amplifying of very wide frequency bands more particularly for television purposes comprising a primary and a secondary winding connected between the circuits to be coupled and coupled so tightly as to have a wide frequency resonance curve corresponding to the desired width of frequency band produced by reason of the arising two coupling waves, said primary and secondary coils the resonant frequencies of which are determined by the inherent capacities being arranged in single-layer

fashion co-axially on the same axis, said primary being divided into two winding coils arranged on either side of the secondary and wound in the same direction, the high potential ends of one of said primary coils and of the secondary being arranged closely to one another so that the additional capacity coupling between said one primary coil and the secondary is more effective between said one primary coil and said secondary than between the other primary coil and said secondary, said windings being arranged movable in their situation one relative to the other for varying the spacing between primary and secondary.

15 3. A high frequency transformer for coupling amplifier circuits used for uniform amplifying of very wide frequency bands, more particularly for television purposes comprising a primary and a secondary winding connected between the circuits to be coupled and coupled so tightly as to have a wide frequency resonance curve corresponding to the desired width of frequency band produced by reason of the arising two coupling waves, said primary and secondary coils the resonant frequencies of which are determined by the inherent capacities being arranged in single-layer fashion co-axially on the same axis, said primary being divided into two winding coils arranged on either side of the secondary and wound in the same direction, the high potential ends of one of said primary coils and of the secondary being arranged closely to one another so that the additional capacity coupling between said one primary coil and the secondary is more effective between said one primary coil and said secondary than between the other primary coil and said secondary, said windings being arranged movable in their situation one relative to the other for varying the spacing between primary and secondary.

20 4. A high frequency transformer for coupling amplifier circuits used for uniform amplifying of very wide frequency bands, more particularly for television purposes comprising a primary and a secondary winding connected between the circuits to be coupled and coupled so tightly as to have a wide frequency resonance curve corresponding to the desired width of frequency band produced by reason of the arising two coupling waves, said primary and secondary coils the resonant frequencies of which are determined by the inherent capacities being arranged in single-layer fashion co-axially on the same axis, said primary being divided into two winding coils arranged on either side of the secondary and wound in the same direction, the high potential ends of one of said primary coils and of the secondary being arranged closely to one another so that the additional capacity coupling between said one primary coil and the secondary is more effective between said one primary coil and said secondary than between the other primary coil and said secondary, said windings being arranged movable in their situation one relative to the other for varying the spacing between primary and secondary.

25 5. A high frequency transformer for coupling amplifier circuits used for uniform amplifying of very wide frequency bands, more particularly for television purposes comprising a primary and a secondary winding connected between the circuits to be coupled and coupled so tightly as to have a wide frequency resonance curve corresponding to the desired width of frequency band produced by reason of the arising two coupling waves, an insulated ring of conductive material, said primary and secondary coils the resonant frequencies of which are determined by the inherent capacities being arranged in single-layer fashion co-axially on the same axis, said primary being divided into two winding coils arranged on either side of the secondary and wound in the same direction, the high potential ends of one of said primary coils and of the secondary being arranged closely to one another so that the additional capacity coupling between said one primary coil and the secondary is more effective between said one primary coil and said secondary than between the other primary coil and said secondary, said ring of conductive material being slotted in one place along a plane, passing through its axis and being arranged movable partly over said one primary coil and said secondary.

30 6. A high frequency transformer for coupling amplifier circuits used for uniform amplifying of very wide frequency bands, more particularly for television purposes comprising a primary and a secondary winding connected between the circuits to be coupled including inherent circuit capacities and coupled so tightly as to have a wide frequency resonance curve corresponding to the desired width of frequency band produced by reason

of the arising two coupling waves, said primary and secondary coils being arranged in single-layer fashion co-axially on the same axis, said primary being divided into two winding coils arranged on either side of the secondary and wound in the same direction, the high potential ends of one of said primary coils and of the secondary being arranged closely to one another so that the additional capacity coupling between said one primary coil and the secondary is more effective between said one primary coil and said secondary than between the other primary coil and said secondary, said windings being arranged movable in their situation one relative to the other for varying the spacing between primary and secondary and said primary having in parallel with its terminals an ohmic resistance, which is smaller than the smallest impedance between the primary terminals, the secondary coil being aperiodically damped, and the natural wavelength of the secondary coil being selected to be shorter than the natural wavelength of the primary coil, both measured in conjunction with the appertaining inherent circuit capacities.

35 7. A high frequency transformer for coupling amplifier circuits used for uniform amplifying of very wide frequency bands, more particularly for television purposes comprising a primary and a secondary winding connected between the circuits to be coupled and coupled so tightly as to have a wide frequency resonance curve corresponding to the desired width of frequency band produced by reason of the arising two coupling waves, an insulated ring of conductive material, said primary and secondary coils the resonant frequencies of which are determined by the inherent capacities being arranged in single-layer fashion co-axially on the same axis, said primary being divided into two winding coils arranged on either side of the secondary and wound in the same direction, the high potential ends of one of said primary coils and of the secondary being arranged closely to one another so that the additional capacity coupling between said one primary coil and the secondary is more effective between said one primary coil and said secondary than between the other primary coil and said secondary, said ring of conductive material being slotted in one place along a plane, passing through its axis and being arranged movable partly over said one primary coil and said secondary.

40 8. A high frequency transformer for coupling amplifier circuits used for uniform amplifying of very wide frequency bands, more particularly for television purposes comprising a primary and a secondary winding connected between the circuits to be coupled including inherent circuit capacities and coupled so tightly as to have a wide frequency resonance curve corresponding to the desired width of frequency band produced by reason
